COUNTERBALANCED APRON FOR PLANERS AND THE LIKE

John M. Walter, Cincinnati, Ohio, assignor to The
G. A. Gray Company, Cincinnati, Ohio, a cor-
poration of Ohio

Application November 30, 1946, Serial No. 713,325

7 Claims. (Cl. 90—54)

1

My invention relates to aprons, otherwise called clapper blocks such as are used in metal planers, the function of which is to hold the cutting tools, and further to pivot so as to lift the tools from working engagement with the material being planed, during the return stroke of the bed on which the material is supported.

The object of the present invention is to provide a spring counterbalance for the apron or clapper block. It is also an object to provide such a counterbalance as will exhibit a minimum of fluctuation in its supported load throughout the angle to which such an apron is likely to be shifted during the return stroke of the machine.

A further object is to make economical provision for the above improvements, ready adjustability and strong and sturdy construction.

The particular construction of the tool box (called often clapper box) and the apron, to be used with my improvement, does not have special importance. I have shown the invention as applied to a construction which in part at least is shown in my application for letters Patent Serial No. 653,223, filed March 8, 1946, now Patent No. 2,489,942, granted Nov. 29, 1949, but this is essentially for purposes of illustration.

In the drawings:

Figure 1 is a front elevation showing the tool box and apron, with the counterbalance of my invention applied.

Figure 2 is an end elevation taken from the side of the counterbalance spring.

Figure 3 is an enlarged fragmentary sectional view taken on the line 3—3 of Figure 2.

The tool box or clapper box of the device is illustrated generally at 1, having side walls 2, 2, thus forming a cavity in which the apron 3 or clapper block is mounted by means of a mounting pin 3a held between the two side walls at a position to engage pivotally the upper end of the apron. The apron is shown as a solid block of metal 3 having the tool mounting clamp bars 5 on its outer face, said bars held on studs 6. As in normal construction, there are shoes secured by suitable rivets to the face of the apron. The illustrated example shows a normal lower shoe 6a, and for the upper shoe shows one indicated at 7, which projects laterally from the apron as at 7a, for a purpose to be described. As in my application for letters patent above referred to, the lower end of the apron is shown as having a projected lower end 8 which engages in an undercut pocket in the tool box lower edge. It will normally be desirable to form the mounting pin for the apron with a slight taper, and to bore the top of the apron with a matching hole.

Mounted near the top of one of the side walls there is provided a spring pilot piece 9. This piece is located on the axis of the mounting pin for the apron, and has a head 10 bolted to the

2

side wall of the tool box, with a cavity 11 to clear the end of the apron mounting pin. The main body of the piece 9 is cylindrical and arranged to support a helical spring 12. The end 9a of the pilot piece is shown as reduced in diameter and provided with a collar 13.

The spring 12 has an end 12a turned at right angles which enters a hole in the collar 13, provided for that purpose. There is a radial hole 14 in the collar for insertion of a tool to adjust the position of the collar, and set screws 15, preferably at two locations, serve to hold the collar in adjusted relation on the end 9a of the pilot piece.

The other end of the spring is projected sufficiently as at 4 to be located in back of the lateral projection 7a of the shoe 7 on the apron. The thickness of the apron with reference to the side walls of the tool box is such that this shoe does not prevent the seating of the apron against the face of the pocket formed in the tool box by the two side walls and the main body of the box.

It will be noted that the spring tends to raise the apron from its seat in the tool box and thus to counterbalance the weight of the apron when it is swung outwardly to clear the work on its return stroke. The apron is shown as provided with a tilting device in the form of a sliding pin 17 in a sleeve type bolt 16 held in the tool box. When using a lifter mechanism it is highly desirable to make it of light construction, and the use of a counterbalance as now described permits this. No particular type of lifter is required, however, and hence I have illustrated only a pin, as noted above. Also the use of one of the shoes on the apron as an abutment for the spring, while convenient, is only optional. Any lateral projection will serve.

A torsional spring such as is used, (in this instance with six turns on a fairly large radius), is long enough so that its action is about the same with reference to the load on the apron when it is swung out at various angles. As is apparent the structure shown could be placed at each side of the tool box instead of on one side only.

The mounting piece 10 could be omitted and the torsion spring and collar could be mounted directly on the swivel pin, if the swivel pin were fixed against rotation in the tool box.

If the swivel pin was tight in the apron and free in the tool box, the torsion spring and collar could then be mounted on the swivel pin and one end of the torsion spring would be engaged with the tool box so as to rotate the swivel pin to counterweight the apron.

When a mounting piece, such as shown on the drawing, is used, this piece could be mounted off center from the swivel pin. By this we mean that

the mounting piece would not have to be co-axial with the swivel pin, but instead could be mounted at a lower position on the side of the tool box. The position of the mounting piece shown on the drawing was chosen because it puts the spring out of the way where it interferes the least in normal operation of the machine.

Having thus described my invention, what I claim as new and desire to secure by Letters Patent is:

1. In combination a tool box having a seat, an apron pivotally mounted at its upper end on the tool box to rest against said seat during a cutting stroke, and arranged for mounting of tools thereon, a torsion spring secured to the apron, and having an end abutting the tool box so arranged as to exert energy in the direction of swinging the apron on its pivot to raise the apron from its seat to counterbalance the weight thereof during a return stroke.

2. The combination of a tool box and an apron pivotally mounted thereon, a mounting piece for a helical spring secured to the tool box, and a helical spring thereon having an end engaging the apron in a direction to exert the torsional effect of said spring in opposition to the weight of the apron.

3. The combination of claim 2 in which the apron is provided with a lateral projection behind which the spring end is in abutment.

4. The combination of claim 2 in which the other end of the spring is retained in a member adjustable in its position on the mounting piece.

5. The combination of claim 2 in which the other end of the spring is inserted into a collar, said collar mounted so as to be adjustable around

the mounting piece, and means for holding the collar in adjusted position.

6. Mounting means for a helical spring on the side of a tool box in planers, for the purpose described, comprising a mounting piece cylindrical as to body to receive a helical spring, having a head secured to said side, said mounting piece having a reduced cylindrical portion at the end, a collar on said reduced cylindrical portion, said collar having a lateral orifice position to receive a right angle bent end of a helical spring when arranged over the body, and means for retaining said collar in adjusted position on said reduced cylindrical portion.

7. In combination a tool box, an apron pivotally mounted at its upper end on the tool box and arranged for the mounting of tools thereon, and a torsional spring engaged as to its helical portion on one of said parts, and engaged at an end thereof to the other of said parts, said spring arranged to exert its force to tend to lift the apron from a depending position on the tool box.
